UNITED STATES PATENT OFFICE.

FRANK J. HERRICK, OF NEW BRITAIN, CONNECTICUT, ASSIGNOR OF ONE-HALF TO H. C. NOBLE, OF SAME PLACE.

DESIGN FOR A SHOE OR GLOVE CLASP.

SPECIFICATION forming part of Design No. 12,382, dated August 2, 1881.

Application filed July 1, 1881. Term of patent 3½ years.

To all whom it may concern:

Be it known that I, FRANK J. HERRICK, a citizen of the United States, residing at New Britain, in the county of Hartford and State of Connecticut, have invented and produced a new and original Design for Shoe or Glove Clasp, of which the following is a specification, reference being had to the accompanying drawings, forming part thereof.

10 Figure 1 is a plan view of my newly-designed clasp; Fig. 2, a side elevation, and Figs. 3 and 4 are plan views of the two parts when detached from each other.

A designates the clasp-lever, B its plate, and 15 C the eye-plate.

The top of the clasp-lever A is ornamented by a border-groove which extends along by the edge of two sides and the rounded end, inside of which border-groove oblique grooves 20 cross each other, dividing the space into diamond and half-diamond shaped figures. In each of said figures I form a circular groove, leaving a small round bead in the space enclosed thereby.

25 The part C has a crescent-shaped piece, a, connected to it by a narrow neck, which piece a will show only upon the opposite side of the leather or fabric when the plates are secured thereto. In the middle of the plate C there is 30 an orifice in the form of a key-hole, the same being bordered by a groove a little distance from the edge of the hole, but parallel thereto. The eye b is oval, and a groove follows around near the edge of all that part of the plate C 35 which is one side of the eye b. Upon each side of the key-hole-shaped orifice there is a row of circular depressions, at the end of which is a circular groove and small bead like those on the lever A.

40 The plate B has a V-shaped opening under

the lever, by the edges of which opening there are parallel grooves. The two sides and end opposite that to which the lever A is hung have grooves near the edge, which, with the grooves by the side of the V-shaped opening, 45 form triangular figures, each of which are ornamented by a row of circular depressions and sunken circle, similar to those on plate C. A crescent-shaped piece, a', like that on C, is also formed at the end of B. 50

I claim—

1. The design for a shoe or glove clasp herein shown and described, the same consisting of the border-groove, oblique grooves crossing each other on the face of the lever A, and 55 the circular ornaments in the diamond and half-diamond shaped figures formed by said grooves.

2. The design for a shoe or glove clasp herein shown and described, the same consisting 60 of the plate B, having the V-shaped opening, the bordering-grooves which inclose triangular-shaped spaces on each side thereof, and the rows of circular ornaments.

3. The design for a shoe or glove clasp herein shown and described, the same consisting 65 of the plate C, having eye b, the central ornamental opening, the border-groove, and the rows of circular ornaments upon the sides of the central opening. 70

4. The design for a shoe or glove clasp herein shown and described, the same consisting of the lever and two plates having ornamental faces, and the crescent-shaped pieces a a' at the ends of the plates B C.

FRANK J. HERRICK.
